METHOD FOR SHRINKING CLOTH

Henry A. Woodhead, Graniteville, S. C.

Application November 24, 1934, Serial No. 754,575

33 Claims. (Cl. 26—19)

This application is a continuation in part of my copending application Serial No. 674,495, filed June 6, 1933, and relates to process and apparatus for preshrinking cloth for the purpose of substantially eliminating shrinkage in both weft and warp in subsequent laundering operations. By means of my process and apparatus I may obtain in a fabric dimensions and characteristics that have been predetermined by carrying out a test laundering on a representative unit portion of the fabric.

There have been several attempts to obtain a satisfactory preshrunk cloth. These methods of preshrinking consisted, for example, in wetting the cloth and permitting shrinkage to take place while the cloth was hung in loops from suitable frames; in imposing a certain crinkle on one set of yarns by pulling out the opposite set of yarns by means of a tentering frame or similar apparatus; or in affixing the cloth to the surface of a relatively thick carrier blanket while the blanket is flexed to a convex position and subsequently flexing the blanket to a concave position to diminish its surface and effect a change in the superficial dimensions of the web warpwise thereof. However, all of these various methods have entailed numerous disadvantages both in the operation of the apparatus and in the characteristics imposed upon the fabric as is more fully discussed in my earlier application.

The speed of the prior art apparatus, for example, was found to be limited thus producing preshrunk fabric at only a relatively low rate.

Another important disadvantage of the prior art shrinking processes is that they are incapable of carrying out the steps of sizing, shrinking, and finishing in one continuous unitary operation, but rather the fabric must be sized, then dried, then again moistened and shrunk, and finally, finished or set.

Among the disadvantageous characteristics imparted to the fabric has been an excessive shrinking in one direction and substantially none in the opposite direction, and furthermore the control of the preshrinking imposed upon the material was difficult to maintain, and incapable of producing a preshrunk fabric in which equilibrium conditions had been obtained. Thus, an unsatisfactory product resulted, having undesirable characteristics in that it was not uniform, nor capable of retaining its preshrunk condition.

One of the primary objects of my invention is to overcome the disadvantages of earlier processes and obtain a preshrunk fabric which is capable

of retaining its preshrunk condition in subsequent laundering operations.

Another object of my invention is to obtain a positive, continuous preshrinking operation that is effective under all conditions to impose a uniform and satisfactory preshrunk condition in a web and one in which equilibrium conditions are established.

Another object of my invention is to obtain an apparatus that is relatively simple to operate and which may be readily adjusted and controlled to vary its effect upon the web to impose a preshrunk condition thereon as circumstances may require.

Another object it is to obtain a process and apparatus in which sizing, complete readjusting and preshrinking and setting of the fabrics are carried out in a single continuous operation.

Other objects and advantages will become apparent upon consideration of the following description and claims when read in conjunction with the accompanying drawings of an illustrative embodiment of my invention.

In my process, the treated fabric is forced by mechanical working and rearrangement of the component yarns, both warp and weft, into a contracted and reconstituted condition of equilibrium in which it is substantially immune from further contraction and rearrangement due to the wetting and working of a subsequent laundering operation. I have found that the shrinkage resulting from laundering operations is not due solely to increased crinkle which may be induced in the warp or weft yarns but that it is also due to a physical rearrangement and readjustment of the yarns and fibers due to the mechanical working and reconditioning and flexing of the fabric in all directions while in its plastic condition during laundering. It is this rearrangement of the warp and weft yarns which I obtain by mechanically working the fabric rapidly and positively. My process for preshrinking is preferably carried out after the usual preliminary steps, such as singeing, removing the warp sizing, bleaching, dyeing, printing, mercerizing, drying, calendering and polishing, or other customary operations have been performed upon the web so that no subsequent operation is necessary which might impair the full advantages of the preshrunk condition attained.

In the drawings:

Figure 1 is a side elevational view in simplified diagrammatic form of part of one form of apparatus suitable for carrying out the preshrinking process in accordance with the invention.

- Figure 1a is a continuation of Figure 1 and shows other parts of the apparatus; 5
- Figures 2 and 2a are plan views of the apparatus shown in Figures 1 and 1a, respectively, with certain parts omitted in order to more clearly show the driving mechanisms for the apparatus. 10
- Figure 3 is an enlarged fragmentary sectional view of a portion of the apparatus illustrated in Figure 1 and shows the web-working means; 15
- Figure 4 is a sectional view on the line 4—4 in Figure 3; 20
- Figure 5 is a detail plan view of the web-working means shown in Figures 1, 3, and 4; 25
- Figure 6 is a sectional view on the line 6—6 of Figure 5; 30
- Figure 7 is a fragmentary sectional view on the line 7—7 in Figure 5; 35
- Figure 8 is a fragmentary plan view of a portion of the apparatus shown in Figure 1a; 40
- Figure 9 is a detail front elevational view of apparatus auxiliary to the web-working means shown in Figures 1, 3, and 4; 45
- Figure 10 is a side elevational view corresponding to Figure 9; 50
- Figure 11 is a diagrammatic outline of a modified form of my preshrinking apparatus; 55
- Figure 12 is also a diagrammatic outline of another form of my preshrinking apparatus; and 60
- Figure 13 is a detailed view of a portion of the apparatus shown in Figure 12. 65
- Referring now more particularly to the drawings in which like reference characters denote like parts, Figures 1 and 1a illustrate a preferred form of my apparatus suitable for carrying out my preshrinking process. 70
- There is indicated by the dotted line 10 the center line of a fabric or web passing through this apparatus. The web 10, which it is assumed may have previously been subjected to processing, such as bleaching, dyeing, printing, calendering, etc., or combinations thereof, is drawn from a truck or bin 1 over an idler roll 2, and preferably between the brush rollers 3 acting as a cleaning device and which removes dust, lint, loose threads, etc., from the surface of the fabric web. This removed matter is carried away by a suction duct 4. From the cleaning device the web is drawn over an idler roll 5 to a plasticizing or sizing apparatus comprising a vat or trough 6 containing a suitable wetting or sizing solution and provided with an idler roll 7 and presser rolls 8, 9. The latter roll, at least, is positively driven from the driving motor 11 for the apparatus, through a suitable speed regulating mechanism, such as a Reeves "variator" as indicated at 12 in Fig. 2, by means of a chain 13 operated from the variable speed shaft 14 of variator 12. 80
- In passing through the sizing solution, which may be of starch, dextrin, gums or soluble oils 60 customarily used in finishing operations, the web is moistened and converted into a plastic, soft condition so that it may be readily worked upon in passing between a "compressing" roll 30 and a feed roll 31, to which it is directed after passing through a tensioning frame 20. 85
- Prior to the compression roll 30, however, there is a frame carrying fixed guide rolls 21, 22 and an intermediate, movable compensator roll 23, the weight of which stretches all the goods to substantially the same degree so that goods of uniform tension and stretch are fed to the rolls 30 and 31. 90
- The tensioning frame 20 is provided with a pair of fixed sprocket wheels 24 and an associated endless chain 25 to which one end of the shaft of 75 compensator roll 23 is connected. This sprocket and chain arrangement is duplicated at the other side of the tensioning frame so that lowering or raising of either end of roll 23, as web slack accumulates or is taken up, results in driving the chains 25 to effect a corresponding movement of the other end of roll 23. In this way the roll 23 is maintained on an even keel to assure proper guiding of the web and obviate sidewise skewing thereof. 100
- The shaft 26 which carries the lower sprocket wheels 24 is also provided with an additional sprocket wheel 27, Fig. 2 acting through a chain 28 and sprocket wheel 29 to move the control member 17 of the variator 12 inwardly or outwardly when roll 23 moves upwardly or downwardly, respectively, suitable mechanism being provided for converting the rotary motion imparted by chain 28 into an axial movement of the member 17. The inward or outward movement 15 of the control member 17 in response to the movement of roll 23 as web slack is taken up or accumulates causes relative axial movement of the discs 18 of the variator. This results in an increase or decrease in the effective diameter of the pulley-like member formed by the discs 18 of the variator with respect to the constant speed pulley thereof in such manner that the associated belt or chain 19 drives the variable speed shaft 13 of the variator at an increased or decreased speed 20 for speeding up or slowing down the operation of the driven roll 9 of the sizing apparatus as web slack is taken up or accumulates. Thus, the movements of the compensator roll 23 of tensioning frame 20 automatically regulate the speed 25 of operation of the sizing apparatus 8, 9 with respect to the rate of operation of the compressing roll 30 and feed roll 31. 30
- The compressing roll 30, shown in Figs. 3 and 4 is similar to one of the several forms described in my earlier application and is made up of a plurality of closely-positioned, thin, toothed discs 32 and intermediate spacers 33 fitted upon a shaft 34 and pressed tightly together thereon. The discs 32 may be made of stainless steel and the teeth 35 thereof are preferably relatively fine, pointed at their ends, beveled on the sides and slightly undercut to permit ready penetration of the cloth web and yarn components, or at least firm gripping thereof without injury or tearing 50 upon entry and withdrawal. 40
- The spacers 33 of roll 30 are slightly smaller in diameter than the discs 32 and thus provide shallow channels through which a plurality of spring fingers 36 extend. The spring fingers are 45 carried by an adjustably mounted transversely extending clamp bar 37. The construction and arrangement of clamp bar 37 will be more fully described later. The fingers 36 extend into engagement with the web and hold it in contact 55 with the working surface provided by an endless blanket 38, preferably of rubber or like material, that extends around roll 31 and a guide roll 39. The fingers 36 may be made of a flexible material, such as stainless steel, and do not exert 60 any material frictional resistance upon the web, particularly when it is in a moist plastic condition due to a starch sizing operation, so that the web slides along the surface formed by these fingers. If desired, the fingers 36 may be replaced by a 65 sectional, web-retaining band, such as those described in my copending applications Serial No. 674,495, filed June 6, 1933, now Patent No. 1,982,720 dated December 4, 1934, or Serial No. 754,576, filed November 24, 1934. Means design- 75

nated as a whole by the numeral 67 of Figure 1 are provided for removing the work roll 30 and fingers 36 as a unit from cooperative relation with roll 31. This means will be described later and 5 is shown in detail in Figures 9 and 10.

The lower roll 31 is driven from the constant speed shaft 15 of variator 12 through a chain 16. The upper or compressing roll 30 is also positively driven but at a higher speed than the feed 10 roll 31. Roll 30 may be driven from the constant speed shaft 15 of variator 12 through suitable speed adjusting mechanism to permit the ratio of the speeds of rolls 30 and 31 to be readily varied as desired. As illustrated in Figs. 2 and 9, the 15 shaft of roll 31 is provided with a gear 81 which actuates intermediate gearing 82 to drive a gear 80 on the shaft 34 of roll 30. The gear 80 is removable to permit substitution of other gears for obtaining a desired ratio between the speeds 20 of rolls 30 and 31, as will be more fully described later. As a result of the higher speed of roll 30, the web, when gripped by its teeth, is carried forward at a faster rate than that at which it would otherwise be advanced by roll 31, the wetted rubber 25 surface of the blanket 38 that extends around roll 31 permitting a slight slippage of the web thereon. Thus, while fingers 36 bearing against the web and forming a web-retaining zone with the blanket 38 exert a restraining force that acts 30 to prevent flexing or crinkling of the surface of the web, roll 30 acts to force the web forward into the zone where it is confined between fingers 31 and blanket 38 and works the cloth to effect a mechanical readjustment of the component 35 yarns. The teeth 35 of roll 30 on entering the cloth pass into and between the fibers of both warp and weft yarns tending to loosen them and exert a shoving action that positions the weft 40 yarns more closely together and acts longitudinally of the warp yarns to shove them together into a fatter or thicker state, i. e. with increased diameters, with the result that the web is contracted or compressed warpwise. This warpwise 45 compression of the web by the roll 30 relieves the web from the tension previously imposed on the warp yarns as a consequence of having been drawn through other processing apparatus.

On leaving the rolls 30, 31, the web is supported 50 by blanket 38 which extends to a position closely adjacent the web-gripping elements 83 of a tentering frame 84 that acts to stretch the web weftwise to approximately the width desired in the final preshrunk material. Suitable means, such 55 as spreading rolls, may be provided to properly guide the side edges of the web for engagement by the gripping elements 83. If desired, other types of devices for stretching the cloth weftwise may be employed, such, for example, as a series 60 of Mycock expanding rollers, preferably positively driven to minimize warp tension.

The tentering frame is of conventional construction and is driven from the variable speed shaft 14a of the main variator 12A by means of a chain 85. The constant speed shaft 15 of variator 12, from which rolls 30, 31 are operated, also is driven by the variable speed shaft 14a of variator 12A through a chain 86. Thus, the tentering frame 84 is operated at the same rate or, as mentioned hereafter, at a fixed ratio to the rate 65 at which the web is delivered from the rolls 30 and 31.

The main variator 12A is similar in construction to the variator 12 described above and its constant speed shaft 15a is driven by motor 11 through a chain 87. Thus, the basic speed of

the entire apparatus may be regulated by adjustment of the control member 17a of main variator 12A to regulate the rate of operation of the variable speed shaft 14a thereof by motor 11.

The blanket 38 extends to tentering frame 84 5 for supporting the web so that the compression of the web effected by the roll 30 is retained to a large degree and is only slightly diminished by warpwise tension on the web as a result of its passing to the tentering frame. The weftwise stretching 10 of the web is facilitated as a consequence of the preliminary relief of warp tension that results from the warpwise compression of the yarn components of the web effected by the roll 30. Thus, the weftwise stretching of the web does not 15 strain the warp yarns as might occur with some types of materials in the event they were passed through a tentering frame in the state of warp tension normally existing after a number of processing steps have been performed. Moreover, by 20 carrying out the weftwise stretching of the web after first effecting a warpwise compression thereof, I render it possible to at least partially retain the preshrinking effect attained by warpwise compression of the web. 25

The tentering operation acts to bring the web out to the desired width of the final product. The prior normal processing steps tend to diminish the width of the web below that which is normal for the fabric. The compression or working 30 operation on the roll 30 does not affect the width of the fabric but only its warpwise dimension. Thus, the tentering operation restores the normal or desired width to the web and in cooperation 35 with the first compressing operation acts to work and adjust both warp and weft yarns to a condition approaching equilibrium.

From the delivery end of tentering frame 84, the web is carried forward by a short endless conveyor 88, driven at the same rate as tentering frame 84 by means of a chain 89. The web is delivered from this conveyor to a second preshrinking or compressing stage comprising another compressing roll 30a and feed roll 31a driven by a chain 90 from the variable speed shaft 14b 40 of a variator 12B. The variator 12B is operated by chains 85 and 85b from the variator 12A. In passing from conveyor 88 the surface of the web is lightly contacted by a balanced tensioning roll 91 which removes any slack from the web, 45 smoothes its surface and guides it under even tension into the feed roll 31a and compressing roll 30a.

Roll 30a, Fig. 1a, is similar to the roll 30 and, as in the previous compressing stage, an endless 50 supporting blanket 38a extends around roll 31a and a guide roll 39a. However, in the second stage the web is in contact with and supported by an endless blanket or band 92, of canvas or other suitable material, also directed around feed 55 roll 31a and overlying the blanket 38a. Band 92 constitutes one of the endless drying blankets forming part of a drier 93 having sets of drying cams 94 operated at the same rate as feed roll 31a by a chain 95 driven from the variable speed 60 shaft 14a of variator 12B.

Although, as shown in Figs. 3 and 4, the teeth of the rolls 30, 30a preferably do not penetrate the web to an extent sufficient to contact the surface of the blanket 38 or band 92, respectively, 70 and thus tend to damage the latter by scoring or tearing their surfaces, it may be desirable in some cases to protect the seams of the band against being torn by the teeth of the work roll 30a. As shown in Figure 8, the band 92, for example, may 75

be provided adjacent its side edges with raised members 95, of leather, canvas or other suitable material, that extend across the seams joining contiguous sections 92a, 92b of the band 92. 5 These raised members 95 engage with collars 96 adjacent the ends of roll 30a to effect a slight compression of the band or lifting of the roll 30a in passing beneath the latter so that the stitches of the seams may not be loosened nor torn by 10 the teeth of the roll.

I also utilize in conjunction with the roll 30a a plurality of resilient spring fingers 36a that extend between the toothed discs 32a and bear against the surface of the web and press it against 15 the drier band 92. On passing to the second compressing roll 30a, the web 10 is gripped by the teeth of the discs making up the roll. The teeth of the discs act to work and loosen the fibers of the yarns and compress the web warpwise as described above in connection with the first compressing roll 30. As the web passes to the nip 20 between rolls 30a, 31a, the drier band 92 is brought into contact with the underside of the web so that, in passing through the zone where the teeth of roll 30a approach the band 92, the web is confined 25 between the fingers 36a and band 92. Thus, while the fingers 36a and band 92 form a retaining zone which prevents rumpling or crinkling of the surface of the web, the compression roll 30a forces 30 the web into the retaining zone wherein surface undulations are inhibited and the web is compressed upon itself as the teeth of roll 30a act to compress the web warpwise by exerting a shoving 35 action on the fibers of both the warp and weft yarns.

The web is carried forwardly from rolls 30a and 31a on the surface of drier band 92 which is supported by the carrier blanket 38a that extends forwardly to the first drying can 94. The 40 fingers 36a extend beyond roll 30a to a position closely adjacent an idler roll 97a around which a second drier band 97 is directed into engagement with the upper surface of the web. The drier bands 92, 97 form a web-retaining means so 45 that warpwise tension is avoided and undulations in the surface of the web are prevented.

In passing over the heated drums 94 of the drier, the supported web is dried and set in its treated condition without being subject to further 50 strain. After passing around an idler roll 98, at the end of the series of drying cans, the bands separate and the web is carried by one of them to an oscillating device 99 which folds the finished 55 preshrunk fabric into piles in the bin 100. Tension-control devices 101 and 102, similar to the tensioning device 20 illustrated in Figs. 1 and 2, are provided for the bands 92, 97, respectively, and suitable guide rolls 103 and 104 direct the bands back to the rolls 31a and 97a.

60 The speed regulating variators through which the several parts of my apparatus are operated from motor 11 permit a close regulation and control to coordinate the relative operating speeds of the driven parts of my apparatus that are antecedent and subsequent to the respective speed regulating devices so that tension on the web may be minimized in order that the preshrunk conditions attained in the several stages may not be diminished as the web passes through the apparatus. 65

As mentioned above, the clamp bar 37, which carries the resilient web-contacting fingers 36, is 70 adjustably supported adjacent the web-working roll 30. Referring now to Figures 5 to 7, the clamp bar 37 comprises a pair of spaced bars 40,

41, separated by spacers 42 adjacent each end and secured in assembled relation by bolts 43. Located intermediate the bars 40 and 41 is a resilient strip 44, preferably of rubber, and a bar 45 formed with transverse semi-circular grooves for receiving 5 the rounded shanks of the resilient spring fingers 36. A plurality of bolts or set screws 46 threaded through bar 45 and contacting bar 44 are provided for variably adjusting the pressure applied to bar 45 to securely hold the fingers 36 10 against the resilient strip 44 on bar 41. Bar 45 extends beyond the forward edges of bars 40, 41, as shown in Figures 5 and 6, overlying projecting portions of the shanks of the fingers 36 so that in addition to reinforcing the shanks of the fingers 15 36 it provides means for distributing pressure imposed on fingers 36 along their shanks.

The clamp bar 37 is adjustably mounted at each end on the side members 60 of the frame 61 in which the bearings for web-working roll 31 are 20 mounted. The frame side members 60 are formed with vertical grooves 61 in which blocks 48 are vertically adjustable by means of bolts 49 extending through the side members 60 and slots 50 in the blocks 48. Each block 48 carries a horizontal guide 51, extending towards roll 30, on which slides 52 are horizontally adjustable toward and away from roll 30 by means of bolts 53 extending through the guides 51 and slots 54 in the slides 52. The slides 52 are in turn provided 30 with supporting members 55, shown as discs, on which similar members or discs 56 are rotatably adjustable by means of bolts 57 extending through the discs 55 and arcuate slots 58 in the discs 56. The discs 56 are provided with shelf-like lugs 59 35 on which the end portions of the clamp bar 37 are fixedly supported, as by means of the assembly bolts 43 of the clamp bar, so that the latter extends longitudinally of the axis of work roll 30.

With the above described arrangement, the 40 clamp bar 37 may be adjusted vertically by means of blocks 48 for positioning fingers 36 so that they extend at the same level through the spaces intermediate the toothed discs 32 of roll 30 without frictionally engaging the disc spacers 33 or otherwise interfering with the operation of roll 30. The clamp bar may also be adjusted horizontally by means of slides 52 so that it extends parallel to the axis of roll 30 and also to move the bar toward or away from the 50 roll so that the extent to which fingers 36 project between the discs 32 and/or beyond the roll 30 may be varied as desired. The rotary adjustment permitted by the arcuate slots 58 in discs 56 enables the clamp bar to be rotatably adjusted 55 for causing the spring fingers 36 to engage the web 10 passing over feed roll 31 with the degree of restraining pressure deemed desirable.

It has heretofore been mentioned that the web-working rolls 30, 30a and their associated spring 60 fingers 36, 36a may readily be removed as a unit from the apparatus to enable them to be cleaned. Referring now to Figures 9 and 10, the frame member 61 in which the roll 30, for example, is journaled and on which the web-contacting fingers 36 are supported, is arranged to be readily demounted from the apparatus so that the toothed roll 30 and fingers 36 may be cleaned easily and quickly to remove therefrom any lint, loose threads, etc., accumulated in operation of 70 the apparatus. The frame member 61 normally rests on supports 62 at each side of feed roll 31 adjacent the ends thereof, pins 63 being provided on the supports for engagement with apertures 62a (Figures 5 and 6) in the lugs on the 75

side members 60 or frame 61 for aligning roll 30 with roll 31. Frame 61 is also provided with adjusting screws 64 contacting the supports 62 for adjusting roll 30 vertically with respect to feed roll 31 to effect proper and even spacing of the teeth 35 of roll 30 from the roll 31 in order to obtain a desired and even working action by all the teeth on roll 30 on the fabric web passing over the feed roll 31.

10 The uprights 65 of the machine frame support a pair of spaced tracks 66 on which a carriage 67 is guided. The cross members 68 of carriage 67 support bevel gears 69 meshing with bevel gears 70 fixed to a shaft 71 journaled in bearings mounted on straps 72 carried by the carriage cross members 68. The bevel gears 69 are provided with internally threaded sleeves 73 through which extend threaded portions of rods 74 secured to the side members 60 of frame 61 so 15 that on operation of shaft 71, as by a hand wheel 75, the frame 61 may be raised, lifting roll 30 and fingers 36 from cooperative relation to feed roll 31. The tracks 66 extend outwardly beyond either or both sides of the apparatus so that the 20 frame 61, carrying roll 30 and fingers 36, may be positioned over and lowered into cooperating relation with a brush-roll 76 mounted on a truck 77 and driven by a motor 78. Truck 77 also is provided with pins 63 engageable with the apertures 63a in the lugs on frame members 61 so that the web-working roll 30 and fingers 36 may be properly aligned with brush roll 76 to be cleaned by the latter. Brush roll 76 is mounted on a truck so that it may also be employed 25 for cleaning the other web-working roll 30a and associated fingers 36a. If desired, truck 77 may also be provided with a vat 79 containing a suitable cleaning fluid for use in conjunction with the brush roll 76.

30 I preferably carry out my preshrinking operations as part of the finishing operation upon a fabric, and, although with certain conditions and types of fabric the operation may be carried out while the fabric is in a dry condition, I prefer 35 to have it in a plastic condition. This permits the fabric to be more easily adaptable to the mechanical working which I impose upon it for effecting a rearrangement of the component yarns and fibres and thus attain a preshrunk 40 condition in which the yarns are in a state of substantial equilibrium. While the fabric may be processed in a wet condition resulting from some preliminary operation, or may be made plastic by merely moistening it, I have illustrated and described my preshrinking operation 45 as commencing by passage of the fabric through the sizing apparatus 6-8 in which a final sizing is imparted to the fabric. As a result of this 50 operation the fabric is rendered soft and plastic 55 in preparation for the subsequent steps of my preshrinking process.

Upon delivery from the sizing apparatus, the web is drawn forwardly over the tension-regulating apparatus 20 by the compressing roll 30 and the feed roll 31. It is desirable to minimize tension on the web between these points, and as previously described, this may be effected automatically by compensator roll 23 or through adjustment of variator 12 by an attendant.

60 As the web enters the nip between rolls 30 and 31, the teeth 35 of roll 30 come into contact with the web at an angle to its surface and are forced into the surface of the web. The teeth are so 65 small that they tend to operate not only upon the individual weft yarns but also actually enter

70 between the fibers making up the warp yarns and, since the teeth move in an arc intersecting the plane of the web and enter and leave the latter at an angle to its surface, they tend to pull and work on the component yarns. This operation causes a loosening and readjustment of the yarns and, in view of the fact that the roll 30 is travelling faster than the web is advanced by roll 31, there is a consequent shoving together 75 of the fibers of the warp yarns as well as a compacting operation on the weft yarns that are gripped by the teeth. Inasmuch as this shoving and compacting operation is carried on while the spring fingers 36 pressing the web against the blanket 38 that travels about roll 31 act to prevent undulations in its surface, there is a mechanical readjustment and repositioning of the component yarns of the web, as distinguished 80 from a mere crinkling of the surface and yarns, so that the web is actually compressed and contracted warpwise.

Upon delivery from the working zone between rolls 30, 31, the web is supported by blanket 38 so that it does not sag and thus become subjected to warp tension which might impair the preshrinking contractions imparted thereto by roll 30. The web is then engaged by the gripping elements 83 of tentering frame 84, which may be of any known type although I have shown the standard clamp form. The tenter may be operated at the same rate as rolls 30, 31 to take up the web from blanket 38 at substantially its rate of delivery by rolls 30, 31 so that it is not subjected to warp tension in being carried forwardly 85 by the gripping elements 83.

It is assumed herein that, as a result of being drawn out warpwise in previous processing operations, the weftwise dimension of the web has been decreased, as is usually the case, and therefore, in its passage through the tentering frame 90 84, I cause the web to be drawn out weftwise to approximately the width which I have found will be present in a fabric which has been properly preshrunk in two directions. The warpwise contraction of the web effected by compressing roll 30 has resulted also in a relief of tension, incidental to the web having been drawn out warpwise in passing through various apparatus in preliminary processing operations. This relief of 95 warp tension facilitates the weft-wise drawing 50 out of the web by the tentering frame and enables the operation to be carried on without imposing a warp strain on the fabric or materially diminishing the preshrinking compression effected by roll 30, since the stretching is carried out 55 on the web at a time when it has been relieved of warp strain to such an extent that the drawing out of the weft threads does not materially affect the warp threads.

On leaving the tentering frame 84, the web is 60 supported and advanced by the conveyor 88 without tension being imposed thereon. Any slack in the web is taken up by tensioning roll 91 as it passes to the working zone between compression roll 30a and drier band 92. This band 65 is advanced by roll 31a. The variator 12B enables adjustments to regulate the relative operating speeds of the tenter 84 and rolls 30a, 31a so that the web is taken up at the second working zone at substantially its rate of delivery from 70 tentering frame 84.

In similar manner to that of roll 30, the compressing roll 30a works the web, effecting a loosening of the component yarns and exerting a 75

- shoving action that compacts the weft yarns and compresses the warp yarns while the retaining fingers 38a hold the web against drier band 92 and prevent undulations of its surface. The web 5 is thus further contracted and compressed warpwise to a state approximately its optimum preshrunk condition.
- Since the web is carried forward to the drier between drier bands 92 and 97 travelling at the same speed, it is delivered to the set of drying cans and advanced therethrough, supported by bands 92 and 97, without being subjected to any tension tending to detract from the full effect of the previous preshrinking operations.
- 15 The rate of operation of the drying cans 94 and the feed roll 31a for drier belt 92 is coordinated with that of compressing roll 38a as all derive their driving power from the shaft 14a of variator 12B.
- 20 In passing through the drier, the bands 92, 97 alternately contact the surfaces of the drums 94 and since the radius between the center of a drum and either band is slightly greater when the band is not in contact with the drum, due to the inter-positioning of the other band, each of the bands is slightly flexed a number of times in passing through the drier. As a result of this flexing, there is a sliding movement of the bands relatively to each other and the web which prevents the latter adhering to either band. In being dried between the bands 92, 97 the cloth is compressed only when the bands are passing around a can and in contact therewith. In passing from one drum to another, there is a space, though relatively small, in which the bands are free from contact with either roll and the compression between the two bands is negligible so that the web, which is not under tension, is free at this point to either contract or expand naturally.

- As an illustration of the changes in dimensions that may take place in the drier, I have found that a typical fabric having a grey width of 31 $\frac{1}{2}$ inches decreased to about 28 inches in processing operations antecedent to my preshrinking process. This fabric was stretched to a width of 31 inches at which width it traversed compressing roll 38a and was delivered between the drier bands 92, 97 and in passing through the drier contracted naturally, as described above, to a width of 29 $\frac{3}{4}$ inches, which is the normal shrunk width for this type of fabric. On the other hand I have found that some fabrics laid between the drier bands at a too narrow width expand naturally during drying to their normal shrunk width, and that in some cases the fabric leaves the drier at the width at which it entered, thus indicating that an equilibrium preshrunk condition has been attained in the antecedent preshrinking stages. Thus, the natural contraction or expansion of the web as it is carried along between the two supporting and flexing bands 92 and 97 and around the drying cans 94 may be taken advantage of to effect a final controlled preshrinking step of my process to compensate for any slight over or under contraction or expansion either warpwise or weftwise resulting from mechanical working of the web in the antecedent preshrinking operations. Consequently, when delivered from the drying cans, after being set and dried therein, the web 75 has attained a preshrunk condition in which its component yarns are in a state of substantial equilibrium and immune to further contraction either warpwise or weftwise when the finished fabric is subjected to a subsequent laundering operation.

From the foregoing description, it may be seen that the web travels through my preshrinking apparatus without tension being imposed thereon as a result of its movement due to the fact that the relative speeds of web delivering and take-up parts of the apparatus may be closely controlled and driven and regulated through adjustment of the several speed regulating variators either by an attendant or, if desired, automatically in response to the movements of tension-regulating 10 rolls as set forth.

In Figure 11 I have disclosed an outline of a modification of an apparatus suitable for carrying out my process which, while it makes use of a working roll 105 similar in operation to the rolls 15 38, 38a of Figures 1 and 1a, for operating upon the fabric, yet it has eliminated the web supporting blankets 38, 38a which extend about and move at the same surface velocity as the cooperating roll 31 or 31a. In this modification as 20 illustrated in Figure 11, the web 16 can be delivered from a weft expanding means of any desired type, indicated by the reference character 106. This web is delivered into the nip between the upper working roll 105 and a lower feed roll 25 107 which corresponds generally to the feed rolls 31 or 31a of Figures 1 and 1a. In order that the web may be held between restraining surfaces, I have provided a band 108 of substantially the same type as band 92 of Figure 1a. This band 30 108 acts in cooperation with a drying drum 109 and suitable guide and idler rolls as well as other drying drums are provided although not illustrated. I provide as a means for holding the web against the band 108 flexible wire or spring-like 35 members 110 which are carried by a transversely extending clamp bar 111 and pass between the toothed discs of the roll 105 and lie in recesses therebetween in substantially the same manner as already described and indicated in Figures 1 40 and 1a. The members 110 extend out beyond the nip a considerable distance and lie substantially parallel with the canvas band-supporting surface 108 as can be seen at the retaining zone h. The surface velocity of the roll 107 and band 108 45 is the same as that of the web 16 within the zone h and, of course, is the same as surface velocity of the drying drum 109. The surface velocity, however, of the toothed roll 105 is greater than that of the roll 107 and as a consequence the web 50 is worked upon and shoved forward and compressed in substantially the same manner as in the operation of my device described in connection with Figures 1 and 1a. The web is carried by the band 108 through the zone h and is delivered 55 into close contact with drying drum 109 by the band 108. After the material has been properly dried and set and is in a finished condition, it is delivered to suitable containers, similar to the manner indicated in Figure 1a.

In Figures 12 and 13 I have indicated another modification of my device. In this apparatus the web may be delivered directly on to a suitable working or friction member from weft expanding means or from other prior processing equipment. 65 The working roll 115 may be of the same type as the toothed disc roll 38 already described or may be made for example from card cloth 116 having narrow longitudinally extending spaced portions free from wire bristles. I have indicated in my 70 drawings the use of such card cloth. The web 16 is maintained in close contact with this card cloth by means of flat curved spring-like members 117 which at spaced intervals hold the web to be 75 treated against the curvature of the roll 115.

These curved flexible members 117 may be supported by a central retaining member 118 extending the width of the web.

The web 10 is delivered from the web-working means on to a revolving drum 119 which may, if desired, be covered with resilient material or padding. This drum has following a portion of its surface curvature a heated polished ironing device 120 which has means 121 for supplying heat to the same. At the lower portion of this smooth polished ironing means 120 there are spaced teeth 122 which are adapted to fit into the narrow spaced portions on the card cloth 116 which are free from bristles. These teeth 122, therefore, penetrate below the surface or outer periphery of the working roll 115 and thus act to lift the web 10 from this roll. The free spaces or grooves on the friction roll 115 can be seen at 123 of Figure 13 and also the teeth 122 can be seen extending into these grooves.

In operation, the cloth in a plastic condition is delivered on to working roll 115, if desired, at the proper width after having passed through means for stretching the web weftwise. The working roll 115 is driven at a greater surface velocity than the roll 119 and thus the web is delivered from the roll 115 at a greater speed than it is taken away by the roll 119. Furthermore, the web is held in close contact with the working roll by means of the flexible curved members 117 and thus there is a working and penetrating action on the surface of cloth which further facilitates adjustments in superficial dimensions to a preshrunk condition. After the cloth has passed in between the drum 119 and the curved heated ironing means 120 it is dried and set and given a finished appearance. Subsequent operations performed upon the cloth as well as the prior operations may be similar to those described in connection with the operation of the apparatus outlined in Figures 1 and 1a.

I have shown in connection with these several apparatuses an exaggerated view of cross section of a fabric material. This has been done for the purposes of illustration only and is not to be considered as indicating necessarily the actual modifications imposed upon the fabric.

In carrying out the preferred form of my process, as described above, the web is first moistened and rendered plastic in a final sizing operation, and then warp-strain incidental to prior processing steps is relieved as the first compressing roll 30 effects a warp-wise contraction and compression of the web. The weft-wise dimension desired in the final preshrunk fabric is then obtained by a weft-wise stretching on the tentering frame 84 while at the same time a certain degree of the warp-wise contraction attained in the previous stage is retained due to the fact that the antecedent relief of warp-strain enables the weft-wise stretching to be carried out without materially affecting the warp yarns. The web is then again worked by a second compressing roll 30a to effect a warpwise contraction of the web approximating the optimum condition of the final preshrunk fabric.

As previously mentioned, the gear 80 by which the working roll 30, for example, is driven through the intermediate gearing 82 from the gear 81 on the shaft of feed roll 31 is removable. Thus by utilizing gears with different numbers of teeth the speed ratio between rolls 30 and 31, or 30a and 31a, may be varied to obtain different degrees of preshrinking in the web as desired. For example, if gears 80, 81 each had one hundred teeth no pre-

shrinking effect would be attained but by utilizing gears 80 that have ninety-eight, ninety-three or ninety teeth, driven in each instance from a gear 81 having one hundred teeth, the compressing roll 30 effects preshrinking of the web to the extent of 2%, 7%, and 10%, respectively. The driving arrangement for rolls 30a and 31a is similar.

As a consequence, it is possible to attain the desired final preshrunk condition by effecting different degrees of preshrinking in the several stages. The fabric may be over-shrunk in one stage; the over-shrunk condition removed or reduced in a following stage to a percentage below that finally desired; and a subsequent preshrinking operation then performed to restore the pre-shrunk condition to the percentage finally desired. On the other hand, part of the desired percentage of preshrinking may be effected in one stage and substantially retained and the remainder effected in a following stage. Also the fabric may be over-shrunk, then pulled out to normal and again over-shrunk and pulled out if desired. This working permits full readjustment and the obtaining of equilibrium conditions.

As an illustration of this working a preferred manner of carrying out the preshrinking operations will be described. Assuming that it is desired to preshrink the previously processed fabric to the extent of 6% in its final condition, a warpwise compression and contraction of the web to the extent of 7% may be effected by means of the compressing roll 30. Then by providing a fixed differential between the rates at which the rolls 30, 31 and the tenter frame 84 are operated through the related chains 16 and 85, the tenter frame 84 may be caused to draw the fabric from carrying blanket 38 at a slightly faster rate than it is delivered by rolls 30, 31. This results in exerting a slight pull on the fabric which serves to smooth the fabric by removing therefrom any ripples or crinkles which might have been imposed thereon as a result of and in addition to the close compaction of the weft yarns, and the compression and contraction of the warp yarns, as described above.

In stretching the fabric weft-wise the pulling out of the weft yarns results also in slightly straightening the warp yarns so that the compaction of the weft yarns is reduced somewhat and, as a consequence of the tentering operation, the 7% preshrinking effected by roll 30 might be reduced by approximately 2%, that is, from 7% to 5%. An additional 2% reduction in the shrinking effected might occur in the passage of the web from work roll 30 and feed roll 31 to the tentering frame 84 and from the latter over the web-carrying conveyor 88 to the second working compressing roll 30a due to slight differentials existing between the rates of operation of the several parts. Thus, the preshrinking effect attained by roll 30 has been reduced from 7% to approximately 3%. By driving roll 30a at a differential with respect to the companion feed roll 31a that would effect approximately a 3% compression in this stage, the preshrinking effect attained is restored to the 6% desired in the finished fabric.

It may be noted that when following this procedure the web is mechanically worked and its yarn components readjusted a number of times in a manner simulating the working of the fabric when subjected to laundering operations; the web after being rendered plastic is compressed warpwise by roll 30, it is then pulled out slightly warpwise in being drawn to tenter frame 84, it

is stretched weft-wise and at the same time also pulled out slightly warp-wise by the tentering frame, and then it is again worked and compressed warp-wise by roll 38a.

5 On the other hand, the percentage of pre-shrinking, say 6%, desired in the final finished fabric may be attained by dividing the pre-shrinking effect attained substantially equally between the compressing rolls 38 and 38a so that 10 one effects a part and the other the remainder, while the relative speeds of the several parts of the apparatus are closely controlled to minimize warp-wise tension on the web that might materially reduce the preshrinking effect attained 15 in the several stages.

As an alternative arrangement either of the rolls 38 or 38a may have the teeth of its discs more finely cut, with the result that one of the rolls (i. e. that having the more finely cut teeth) 20 effects a greater degree of web compression and working and readjustment of the component yarns than is effected by the other toothed roll.

In the next stage, as already pointed out, upon passing from the second compressing and contracting stage to and through the drying cans 34, where it is set and dried, the web is free of tension since it is supported and carried between travelling bands 32, 37. In passing 25 through the drying cans the flexing and relative sliding of the drier bands causes the web to be maintained free from adherence to either band. While not compressed between these bands in advancing from one drying drum to another the web is free to contract or expand naturally to a 30 condition in which its component yarns are in a state of equilibrium and practically immune from contraction in laundering operations, if this state of equilibrium has not already been attained in the preceding preshrinking stages of my process.

40 Although I have described my process and apparatus in detail, it will be apparent to those skilled in the art that many changes and variations may be made without departing from the spirit of the invention and, therefore, it is my intention and desire to include all such changes and variations within the scope of the appended claims.

I claim:

50 1. An apparatus for imposing a preshrunk condition on a fabric web which has been subjected to preliminary processing operations comprising; means for wetting the web whereby it is rendered in a plastic condition; retaining means engaging the web to prevent undulations in its surface; means receiving the web from said wetting means for mechanically working and re-positioning its yarns while cooperating with said retaining means to effect a warpwise compression 55 of the web and to relieve warp tension imparted thereto in said preliminary processing operations; means for taking up the web from said working means and stretching it weftwise to substantially the width desired in the final preshrunk fabric; other retaining means preventing undulation of the surface of the web; other means receiving the web from said stretching means for mechanically working and re-positioning its yarns while cooperating with said 60 other retaining means to effect a warpwise compression of the web to a condition in which the weft and warp yarns thereof are substantially in a state of equilibrium and immune to contraction in a subsequent laundering operation; and means receiving the web from said last working means for drying the web in 65 its preshrunk condition.

70 2. An apparatus for imposing a preshrunk condition on a fabric web which has been subjected to preliminary processing operations comprising means of rendering the web in a plastic 75

means for drying and setting the web in its preshrunk condition.

2. An apparatus for imposing a preshrunk condition on a fabric web which has been subjected to preliminary processing operations comprising 5 means for sizing the web whereby it is rendered in a plastic condition; means engaging the web to prevent undulations in its surface; means receiving the web from said sizing means for mechanically working and re-positioning its yarns 10 while held against surface movement to effect a warpwise compression thereof and to relieve warp tension imparted to the web in said preliminary processing operations; means for taking up the web from said working means and stretching it 15 weftwise to the width desired in the final pre-shrunk fabric; retaining means engaging the web to prevent undulating its surface; means receiving the web from said stretching means for mechanically working and repositioning its yarns 20 while cooperating with said retaining means to effect a warpwise compression of the web to a condition in which the weft and warp yarns thereof are contracted to a condition approximating a state of equilibrium; and a web drier receiving 25 the web from said last working means including a plurality of heated drying drums and a pair of travelling bands, one at each side of said web, for supporting and carrying it partially around each of said drums, said bands alternately contacting the curved surfaces of the drying drums so that the bands are repeatedly flexed in reverse directions in passing through the drier, whereby the web is maintained from adhering to either band and is thus free, in being carried 30 from one drum to the next, to contract or expand naturally to a preshrunk condition in which its component yarns are in a state of equilibrium and substantially immune to shrinkage in a subsequent laundering operation.

40 3. An apparatus for imposing a preshrunk condition on a fabric web which has been subjected to preliminary processing operations comprising means for rendering the web in a plastic condition; retaining means engaging the web to prevent undulations in its surface; means receiving the web from said plasticizing means for mechanically working and re-positioning its yarns while cooperating with said retaining means to effect a warpwise compressing thereof and to relieve 45 warp tension imparted to the web in said preliminary processing operations; means for taking up the web from said working means and stretching it weftwise to the width desired in the final preshrunk fabric; other retaining means engaging said web and preventing undulation of its surface; other means receiving the web from said stretching means for mechanically working and re-positioning its yarns while engaged by said other retaining means to effect a warpwise compression of the web, one of said working means being adapted to effect a greater warpwise compression of the web than is effected by the other, both of said working means cooperating to contract the web to a condition 55 in which the weft and warp yarns thereof are in a state of equilibrium and substantially immune to shrinkage in a subsequent laundering operation; and means receiving the web from said last working means for drying the web in 60 its preshrunk condition.

4. An apparatus for imposing a preshrunk condition on a fabric web which has been subjected to preliminary processing operations comprising means of rendering the web in a plastic 75

condition; retaining means engaging said web to prevent undulation of its surface; means receiving the web from said plasticizing means for mechanically working and re-positioning its 5 yarns while cooperating with said retaining means to effect a warpwise compression thereof and to relieve warp tension imparted to the web in said preliminary processing operations; means for taking up the web from said working means and stretching it weftwise to the width desired 10 in the final preshrunk fabric; other retaining means engaging said web to prevent undulation of its surface; other means receiving the web from said stretching means for mechanically 15 working and re-positioning its yarns while cooperating with said other retaining means to effect a warpwise compression of the web to a condition in which the weft and warp yarns thereof are in a state of equilibrium and immune 20 to contraction in a subsequent laundering operation; means receiving the web from said last working means for drying and setting the web in its preshrunk condition; means for positively driving said plasticizing means, said first web 25 working means, said weft stretching means, said second web working means and said drying means; and means for controlling and regulating the relative operating speeds of the various driven means for minimizing and controlling 30 tension on the web in passing through said apparatus.

5. An apparatus for imposing a preshrunk condition on a fabric web which has been subjected to preliminary processing operations comprising; means for sizing the web whereby it is rendered in a plastic condition; means receiving the web from said sizing means for stretching it weftwise to the width desired in the final preshrunk fabric; retaining means engaging the web 35 to prevent undulating its surface; means receiving the web from said stretching means for mechanically working and re-positioning its yarns while cooperating with said retaining means to effect a warpwise compression of the web to a condition in which the weft and warp yarns 40 thereof are contracted to a condition approximating a state of equilibrium; and a web drier receiving the web from said working means including a plurality of heated drying drums and a 45 pair of travelling bands, one at each side of said web, for supporting and carrying it partially around each of said drums, said bands alternately contacting the curved surfaces of the drying drums so that the bands are repeatedly flexed 50 in reverse directions in passing through the drier, whereby the web is maintained from adhering to either band and is thus free, in being carried from one drum to the next, to contract or expand naturally to a preshrunk condition in which its 55 component yarns are in a state of equilibrium and substantially immune to shrinkage in a subsequent laundering operation.

6. In a preshrinking apparatus having means for contracting a web warpwise and means for 60 setting the web in a preshrunk condition, the combination therewith of preliminary apparatus consisting of a gripping means adapted to act within the body of the web and retaining means forming a confined zone and cooperating 65 with said gripping means and acting to inhibit surface undulations in the web, said gripping means being adapted to penetrate, loosen and readjust the yarn components whereby warp tension is relieved; and a weft stretching means 70 taking up the web from said gripping means and

adapted to stretch it to approximately its final width and deliver it to said contracting means.

7. An apparatus for imposing a preshrunk condition on a fabric which has been subjected to preliminary processing operations comprising; retaining means engaging the web to prevent undulation of its surface; means for mechanically working and re-positioning the yarns of the web while cooperating with said retaining means to effect a warpwise compression 10 thereof and to relieve warp tension imposed thereon in said preliminary processing operations; means for taking up the web from said working means and stretching it weft-wise to the width desired in the final preshrunk fabric; a feed roll 15 adjacent said working means; and an endless blanket directed about said feed roll and cooperating with said retaining means to form a web-confining zone in which said working means effect warpwise compression of the web, said 20 blanket extending to said stretching means for supporting and carrying the web for obviating uncontrolled diminishment of the warpwise compression effected by said working means.

8. An apparatus for imposing a preshrunk condition on a fabric web comprising; means for rendering the web in a plastic condition; retaining means engaging the web to prevent undulating its surface; a toothed roll receiving the web from said plasticizing means for mechanically 30 working and re-positioning its yarns while cooperating with said retaining means to effect a warpwise compressing of the web; means for taking up the web from said working means and stretching it weftwise to the width desired in the 35 final preshrunk fabric; other retaining means engaging said web and preventing undulation of its surface; a second toothed roll receiving the web from said stretching means for mechanically 40 working and re-positioning its yarns while engaged by said retaining means to effect a warpwise compression of the web, the teeth of one of said rolls being more finely cut than those of said other compressing roll for effecting a different warpwise compression of the web in one stage 45 than in the other compressing stage and both of said rolls cooperating to contract the web to a condition in which the weft and warp yarns thereof are in a state of equilibrium and substantially immune to shrinkage in a subsequent 50 laundering operation; and means receiving the web from said last roll for drying the web in its preshrunk condition.

9. An apparatus for treating a fabric web to cause readjustment of its component yarns to a 55 condition adapted to minimize change in its superficial dimensions during subsequent laundering operations comprising; web supporting means, web working means having a plurality of spaced rows of web-penetrating projections for 60 gripping and working the web to readjust the positions of its component yarns and effect a warp-wise compression of the web; and a plurality of spaced resilient fingers extending into engagement with the said web adjacent said 65 working means for preventing undulation of the surface of said web and cooperating with said working means to effect warp-wise compression of the web.

10. An apparatus for treating a fabric web to 70 cause readjustment of its component yarns to a condition adapted to minimize change in its superficial dimensions during subsequent laundering operations comprising; web supporting means, web working means having a plurality of 75

spaced rows of web penetrating projections engaging one surface of the web for gripping and working the latter to effect warp-wise compression of the web; and a plurality of spaced resilient fingers extending between said rows of projections on said working means into engagement with said surface of the web for preventing undulation of the web and cooperating with said working means to readjust the positions of the 10 component yarns of the web for effecting warp-wise compression thereof.

11. An apparatus for treating a fabric web to cause readjustment of its component yarns to a condition adapted to minimize change in its 15 superficial dimensions during subsequent laundering operations comprising; web working means having a plurality of spaced rows of web-penetrating projections for gripping and working the web to readjust the positions of its component 20 yarns and effect a warp-wise compression of the web; a feed roll closely adjacent said working means; an endless blanket directed about said feed roll and forming a working surface on which the web is supported and against which said 25 working means operate in compressing the web; and a plurality of spaced resilient fingers extending between the rows of web-penetrating projections on said working means into engagement with the surface of said web and cooperat- 30 ing with said blanket to form a web confining zone in which surface undulations of the web are prevented.

12. An apparatus for treating a fabric web to cause readjustment of its component yarns to a 35 condition adapted to minimize change in its superficial dimensions during subsequent laundering operations comprising; web working means having a plurality of spaced rows of web penetrating projections engaging one surface of the 40 web for gripping and working the latter to effect warp-wise compression of the web; and a plurality of spaced resilient fingers engaging the opposite surface of the web to form with said working means a web retaining zone for substantially preventing undulation of the surfaces of 45 the web and cooperating with said working means to cause readjustment of the yarn components of the web for effecting warp-wise compression thereof.

13. An apparatus for treating a fabric web to cause readjustment of its component yarns to a condition adapted to minimize change in its superficial dimensions during subsequent laundering 50 operations comprising; a web working roll 55 provided with a card-cloth covering having narrow longitudinally extending space portions free from bristles, the spaced longitudinally extending rows of bristles constituting web-working means for gripping and working the web; and web retaining means engaging said web to prevent formation of undulations in the web surfaces and cooperating with said web-working bristles to effect warpwise compression of the web.

14. An apparatus for imposing a preshrunk 60 condition on a fabric web which has been subjected to preliminary processing operations comprising; retaining means engaging the web to prevent undulations in its surface; web-working means provided with a plurality of spaced rows 65 of web-gripping projections adapted to grip the web and cooperating with said retaining means for causing readjustment of the yarn components of the web to effect a warp-wise compression of the latter; and spaced means extending between 70 said rows of web-gripping projections for lifting 75

the web from engagement with said web-gripping projections of said working means.

15. An apparatus for treating a fabric web to cause readjustment of its component yarns to a condition adapted to minimize change in its superficial dimensions during subsequent laundering operations comprising; means for wetting the web whereby it is rendered in a plastic condition; a web-working roll having a plurality of spaced rows of web-penetrating projections for gripping said web and readjusting the positions of the yarn components thereof; a web feeding-roll positioned opposite and closely adjacent said working roll; a plurality of spaced web-retaining means supported at the take-up side of said rolls 15 and engaging the web to prevent undulation of the surface thereof and cooperating with said working roll to effect warpwise compression of the web; and a plurality of spaced members supported at the delivery side of said rolls and extending into the nip formed by the latter for lifting said web from engagement with the web-penetrating projections of said work roll.

16. An apparatus for treating a fabric web to cause readjustment of its component yarns to a 25 condition adapted to minimize change in its superficial dimensions during subsequent laundering operations comprising; means for wetting the web whereby it is rendered in a plastic condition; a web-working roll having a plurality of spaced 30 rows of web-penetrating projections for gripping said web and readjusting the positions of the yarn components thereof; a web-feeding roll positioned opposite and closely adjacent said working roll; a plurality of spaced web-retaining 35 means supported at the take-up side of said rolls and extending into the nip formed by said rolls and engaging the web to prevent undulation of the surface thereof and cooperating with said working roll to effect warpwise compression of 40 the web; and heated means adjacent said feed roll and forming therewith a web-confining zone in which surface undulations of the web are prevented and the web set.

17. In apparatus for imposing a preshrunk 45 condition on a fabric web; web feeding means; web-working means having a plurality of spaced series of web-penetrating projections; a frame supported adjacent said feeding means and provided with side members in which said working 50 means is mounted for positioning the web-penetrating projections thereof to grip and work a web advanced by said feeding means; a plurality of spaced resilient members adapted to extend between the spaced series of projections on said 55 working means into engagement with a fabric web advanced by said feeding means and positioned opposite said feeding means for forming therewith a restraining zone about the web to prevent surface undulations of the latter; holding means for said resilient members; means adjustably connected to said side members of said frame at one side of said working means for supporting said holding means; and means for adjusting said supporting means on said frame for 60 variably positioning said resilient members with respect to said web-working means and said web-feeding means.

18. In apparatus for imposing a preshrunk 65 condition on a fabric web; web feeding means; a 70 web-working roll having a plurality of spaced series of web-penetrating projections; a frame supported adjacent said feeding means and provided with side members in which said roll is journaled for positioning the web-penetrating 75

projections thereof to grip and work a web advanced by said feeding means; a plurality of spaced resilient members adapted to extend between the spaced series of projections on said roll into engagement with a fabric web advanced by said feeding means and positioned opposite said feeding means for forming therewith a restraining zone about the web to prevent surface undulations of the latter; holding means for said 5 resilient members; means adjustably connected to said side members of said frame at one side of said roll for supporting said holding means, said means being adjustable on said frame side members toward and away from said roll for positioning said holding means in parallelism with said roll.

19. In apparatus for imposing a preshrunk condition on a fabric web; web feeding means; a web-working roll having a plurality of spaced 10 series of web-penetrating projections; a frame supported adjacent said feeding means and provided with side members in which said roll is journaled for positioning the web-penetrating projections thereof to grip and work a web advanced by said feeding means; a plurality of spaced resilient members adapted to lie in and extend through the spaces intermediate the series of web-penetrating projections on said roll for engagement with a fabric web carried by said 15 feeding means to exert a restraining force on said web for preventing undulations in the surface thereof; holding means for said resilient members; guide members mounted on the side members of said frame at one side of said roll and 20 extending toward the latter; slides mounted on said guides and supporting said holding means; and means for adjustably connecting said slides to said guides for variably positioning said holding means with respect to said roll for regulating 25 the extent to which said resilient members extend through the spaces between the series of web-penetrating projections on said roll.

20. In apparatus for imposing a preshrunk condition on a fabric web; web feeding means; a web-working roll having a plurality of spaced 30 series of web-penetrating projections; a frame supported adjacent said feeding means and provided with side members in which said roll is journaled for positioning the web-penetrating projections thereof to grip and work a web advanced by said feeding means; a plurality of spaced resilient members adapted to extend through the spaces 35 intermediate the series of web-penetrating projections on said roll into engagement with a fabric web carried by said feeding means to exert a restraining force on said web for preventing undulations in the surface thereof; holding means for said resilient members; supporting means for said holding means carried by the side members of said frame at one side of said roll; and means for rotatably adjusting said supporting means on said frame members to regulate the restraining 40 force exerted by said resilient fingers on a web carried by said feeding means.

21. In an apparatus for treating a fabric web; a web working roll provided with projections adapted to grip and penetrate said web for effecting a mechanical readjustment of the component yarns thereof; a feed roll positioned closely adjacent 45 said working means; an endless web supporting band passing around said feed roll and forming a working surface against which said working roll bears in gripping said web, said band having end edges thereof joined by stitched seams extending 50 transversely thereof; and means on said band for 55 effecting a separation of said band working surface from against said working roll on passage of the seams of said band between said working roll and said feed roll whereby the loosening or tearing of the stitches of said seams by said working 60 roll is prevented.

22. In apparatus for imposing a preshrunk condition on a fabric web; web-feeding means; a unitary web-working assembly adapted to be mounted or detached as a unit from cooperative 65 relation with said feeding means comprising, a frame; a working roll journaled in said frame, said roll having a plurality of spaced series of web-surface penetrating projections adapted to grip and work the web as it is advanced by said 70 feeding means; a plurality of spaced resilient members adapted to extend between the spaced series of web-surface penetrating projections on said roll into engagement with a fabric web advanced by said feeding means and cooperating 75 with said feeding means to form a restraining zone about the web for preventing surface undulations of the latter; and holding means for said resilient members mounted on said frame at one side of said working roll for positioning said 80 resilient members to extend between the spaced series of web-penetrating projections on said roll into engagement with the surface of said web.

23. In apparatus for imposing a preshrunk condition on a fabric web; web-feeding means; a unitary web-working assembly adapted to be mounted or detached as a unit from cooperative 85 relation with said feeding means comprising, a frame; a working roll journaled in said frame, said roll having a plurality of spaced series of web-penetrating projections adapted to grip and work the web as it is advanced by said feeding means; a plurality of spaced resilient members adapted to extend between the spaced series of web-penetrating projections on said roll into engagement with a fabric web advanced by said feeding means for preventing surface undulations of the web; holding means for said resilient members mounted on said frame at one side of said working roll for positioning said resilient members to extend between the spaced series of web-penetrating projections on said roll into engagement with the surface of said web; and means for 90 adjusting said holding means vertically, horizontally and rotatably on said frame for regulating 95 the position of said resilient members with respect to said web-working roll and said web-feeding means.

24. A process for treating a fabric web by performing a series of working operations on said 100 web to cause readjustment of the component yarns to a condition adapted to minimize change in superficial dimensions during a subsequent laundering operation comprising wetting said web to render the same in a plastic condition; mechanically working the web, while inhibiting surface undulations to effect a partial warpwise contraction and compression of the component yarns and to relieve warp tension; stretching the web weftwise while thus relieved from warp tension 105 to the weftwise dimension desired in the finished fabric; mechanically working the web, while inhibiting surface undulations, to effect a warpwise contraction and compression of the web to readjust the positions of the component yarns within 110 the body of the webs to a condition in which the latter are in a state of equilibrium and substantially immune to shrinkage in a subsequent laundering operation; and drying the web in its equilibrium preshrunk condition.

25. A process for treating a fabric web by performing a series of working operations on said web to cause readjustment of the component yarns to a condition adapted to minimize change in superficial dimensions during a subsequent laundering operation comprising wetting said web to render the same in a plastic condition; working the web, while holding its surface against undulating, to effect a partial warpwise contraction and compression of the component yarns within the body of the web and to relieve warp tension; stretching the web while relieved from warp tension to the weftwise dimension desired in the finished fabric; working the web, while holding its surface against undulating, to mechanically readjust the positions of the component yarns within the body of the web for effecting a contraction and compression of the web to a condition in which the component yarns approximate a state of equilibrium and are substantially immune to shrinkage in a subsequent laundering operation; and drying the web under conditions permitting its component yarns to readjust their positions naturally to said state of equilibrium.

26. In a preshrinking operation including the steps of gripping a fabric and readjusting the threads and fibers thereof while forcing it into a retaining zone wherein surface undulations of said web are inhibited whereby a readjusted and preshrunk web is obtained and finally setting the web in its treated condition, the preliminary steps of relieving the warp tension on said web present as the result of prior processing operations by gripping said web and shoving it forward into a retaining zone faster than the normal progress of said web and while loosening and readjusting the yarn components thereof, and subsequently without any intermediate imposition of warp tension on said web, stretching said web weftwise to the approximate final web width desired while relieved from warp tension.

27. A process for treating a fabric web by performing a series of working operations on said web to cause readjustment of its component yarns to a condition adapted to minimize change in superficial dimensions during a subsequent laundering operation comprising sizing the web whereby it is rendered in a plastic condition; mechanically working the web, while holding its surface against undulating, to effect a partial warp-wise contraction and compression of the component yarns thereof within the web and to relieve warp tension; stretching the web weftwise while relieved from tension to substantially the width desired in the final pre-shrunk fabric; mechanically working the web, while inhibiting surface undulation to effect a warp-wise contraction and compression within the web to readjust the positions of the component yarns to a condition in which the weft and warp yarns are in a state of equilibrium and immune to contraction in a subsequent laundering operation; drying and setting the web in its pre-shrunk condition; and maintaining the web substantially free from warp tension while undergoing said working operations.

28. A process for preshrinking a fabric web by performing a series of working operations on said web to cause readjustment of its component yarns to a condition adapted to minimize change in its superficial dimensions during a subsequent laundering operation which comprises; wetting the web to render it in a plastic condition; mechanically working the web, while holding its sur-

face against undulating, to subject the individual yarn components of the web to a shoving, loosening and pulling action, whereby the yarn components are readjusted within the body of the web to compress the web along its length an amount substantially corresponding to the degree of preshrinking desired in the finished fabric; stretching the web weft-wise to substantially the weftwise dimension desired in the final fabric while causing the web to be advanced to and through the stretching zone at a more rapid rate than it is delivered from the working zone, whereby the yarn components are readjusted within the body of the web to reduce the web compression to an amount less than the degree of preshrinking desired in the final fabric; and mechanically working said web, while holding its surface against undulating, to effect a warpwise contraction and compression of the yarn components within the web for restoring the web compression, effected by readjustment of the yarn components, to an amount substantially corresponding to the degree of preshrinking desired in the finished fabric.

29. A process for preshrinking a fabric web by performing a series of working operations on said web to cause readjustment of its component yarns to a condition adapted to minimize change in its superficial dimensions during a subsequent laundering operation which comprises, wetting the web to render it in a plastic condition; mechanically working the web, while holding its surface against undulating, to subject the individual yarn components of the web to a shoving, loosening and pulling action, whereby the yarn components are readjusted within the body of the web to compress the web along its length an amount substantially corresponding to the degree of preshrinking desired in the finished fabric; stretching the web weftwise to substantially the weftwise dimension desired in the final fabric while causing the web to be advanced to and through the stretching zone at a more rapid rate than it is delivered from the working zone whereby the yarn components are readjusted within the body of the web to reduce the web compression to an amount less than the degree of preshrinking desired in the final fabric; and mechanically working said web, while holding its surface against undulating, to effect a warpwise contraction and compression of the yarn components within the web for restoring the web compression, effected by readjustment of the yarn components, to an amount approximating the degree of preshrinking desired in the finished fabric; and drying and setting the web while maintaining it free from warp tension for permitting the yarn components to readjust their positions naturally to a condition in which the web is compressed substantially to the degree of preshrinking desired in the finished fabric and the yarn components are in a state of equilibrium and are substantially immune to shrinkage in subsequent laundering operations.

30. A process for preshrinking a fabric web by performing a series of working operations on said web to cause readjustment of its component yarns to a condition adapted to minimize change in its superficial dimensions during a subsequent laundering operation which comprises; wetting the web to render it in a plastic condition; mechanically working the web while holding its surface against undulating, to subject the individual yarn components of the web to a shoving, loosening and pulling action whereby the

yarn components are readjusted within the body of the web to partially compress the web along its length to an extent less than the degree of pre-shrinking desired in the finished fabric; stretching the web weftwise to approximately the weftwise dimension desired in the finished fabric while maintaining the web substantially free from warp strain to substantially preclude diminishment of the preshrinkage effected in said working operation; mechanically working said web, while holding its surface against undulating, to effect an additional warpwise compression for increasing the compression of the web to approximately the degree of preshrinkage desired in the finished fabric; and drying and setting the web while maintaining it free from warp tension for permitting the yarn components to readjust their positions naturally to a condition in which the web is compressed substantially to the degree of preshrinkage desired in the finished fabric and the yarn components are in a state of equilibrium and are substantially immune to shrinkage in subsequent laundering operations.

31. A process for preshrinking a fabric web by performing a series of working operations on said web to cause readjustment of its component yarns to a condition adapted to minimize change in its superficial dimension during a subsequent laundering operation which comprises plasticizing the web, mechanically working the web while holding its surface against undulation to over-compress the web warpwise, and stretching the web to re-

duce the compression an amount sufficient to obtain a final fabric product having dimensions equivalent to a web in equilibrium and substantially free from further dimensional change upon laundering.

32. A process for preshrinking a fabric web by performing a series of working operations on said web to cause readjustment of its component yarns to a condition adapted to minimize change in its superficial dimensions during a subsequent laundering operation, comprising overly compressing the web warpwise while holding its surface against undulation, and then stretching the web to reduce the compression warpwise to an amount whereby a final fabric product substantially free from further dimensional change upon laundering is obtained.

33. A process for preshrinking a fabric web by performing a series of working operations on said web to cause readjustment of its component yarns to an equilibrium standard condition adapted to minimize change in the superficial dimensions during a subsequent laundering operation which comprises overly compressing the web warpwise while holding the web surface against undulation, stretching the web warpwise to reduce the compression below the desired equilibrium standard and finally again compressing the web warpwise an amount sufficient to produce a fabric product substantially free from further dimensional change upon laundering.

HENRY A. WOODHEAD.
